UNITED STATES PATENT OFFICE.

BRITTAINE F. WALSER, OF WEST SALEM, ILLINOIS.

LIFTING-JACK.

1,332,584.

Specification of Letters Patent.

Patented Mar. 2, 1920.

Application filed April 30, 1917. Serial No. 165,561.

To all whom it may concern:

Be it known that I, BRITTAINE F. WALSER, a citizen of the United States, residing at West Salem, in the county of Edwards, 5 State of Illinois, have invented a new and useful Lifting-Jack; and I do hereby declare the following to be a full, clear, and exact description of the invention, such as will enable others skilled in the art to which 10 it appertains to make and use the same.

This invention relates to an improved lifting jack, particularly adapted for use in connection with automobiles and the like.

As one of the objects of the invention, it 15 is the aim to employ a plurality of lifting jacks of the kind hereinafter set forth, say for instance one for each end of each axle of the motor vehicle, whereby the vehicle may be jacked up bodily, thereby preventing the tires from contacting with the 20 floor of the garage hence saving the tires.

A further object of the invention is to provide an improved lifting jack comprising a body having a guide therein, a lifting 25 member mounted in the guide, and an eccentric member adjustably carried by the lifting member and adapted to cam on the shoulder of the body, for raising and lowering the lifting member.

30 A further object of the invention is the provision of a detachable handle carried by the eccentric member for operating the said member, and which handle may be detached and used for removing and replacing 35 tires upon automobile wheels.

The invention comprises further features and combination of parts, as hereinafter set forth, shown in the drawings and claimed.

In practical fields the details of construction may require alterations falling within the scope of what is claimed.

In the drawings:—

Figure 1 is a view in side elevation of the improved lifting jack constructed in 45 accordance with the invention.

Fig. 2 is a view in side elevation, showing the lifting member raised.

Fig. 3 is a view in elevation of the side of the jack opposite to that shown in Figs. 50 1 and 2, showing the lifting member raised.

Fig. 4 is a sectional view on line 4—4 of Fig. 1.

Fig. 5 is a sectional view on line 5—5 of Fig. 2.

55 Fig. 6 is a detail perspective view of the lever to be carried by the eccentric member.

Referring more especially to the drawings, 1 designates the body of the jack, which is constructed of three sections, preferably of wood and designated respectively by the numerals 2, 3, and 4. The sections 3 and 4 are substantially triangular in side elevation, and are constructed so that the grain of the wood may extend vertically. These sections 3 and 4 are arranged, so that 60 their adjacent vertical edges are spaced from each other, and held so spaced by the section 2, through which and the sections 3 and 4 suitable rivets 5 extend, to hold the parts together. The section 2 is disposed 65 so that the grain of the wood extends transversely of the grain of the sections 3 and 4, thereby preventing warping. By so spacing the sections 3 and 4 a suitable guide 6 is provided for the reception of the lifting 70 section 7 of the jack. This lifting section 7 may be constructed of any suitable material, preferably wood or the like, and where this section is designed to engage the outer portion of the hub of the wheel of the motor 75 vehicle, a suitable bearing member 8 may be attached, thereby preventing wear on the lifting section 7. However, this bearing member 8 may be removed, and dispensed with if desired. Secured by the rivets 9 80 to the sections 3 and 4 and spanning the guide 6 are the metallic straps 10, which act to hold the lifting section in its guide. This lifting section is provided with a plurality of apertures 11, and designed to pass 85 through any one of the apertures is a suitable screw 12, which is threaded into the disk or the lifting section actuating member 90 13. The section 2 of the body is constructed shorter than the sections 3 and 4, and is disposed so that its edge 14 is arranged below 95 the upper ends of the sections 3 and 4, thereby providing a shoulder. The screw 12 is threaded eccentrically into the disk or member 13 as shown. The disk or member 100 13 has two threaded recesses 15, either one of which may receive the screw 12, and in either case the disk or member 13 will be mounted eccentrically. That portion of the screw 12 where it passes through the lifting 105 section 7 is cylindrical, smooth, and unobstructed, and a trifle larger than its threaded part which is threaded into one of the recesses 15. By constructing the parts in this manner, the screw will readily 110 turn with the disk or member 13, so that the screw will turn easily in its aperture of the

section 7. The outer face of the disk or member 13 has constructed thereon an elongated portion 16 provided with a tapered opening 17 rectangular in cross section and 5 constituting a socket for the lever or handle 18. The aim of this invention is to utilize four of these lifting jacks, one for the outer hub portion of each wheel of the motor vehicle, in order to jack up the vehicle bodily, 10 and to keep the tires of the wheels out of contact with the floor of the garage, thereby preventing wear on the tires (which may be previously deflated) while the vehicle is in storage, thereby prolonging the life of the 15 tires. In jacking up a motor vehicle one lever (whose handle end 19 may be employed for removing and applying tires to wheels) may be used for insertion into the socket of the disk 13 of each lifting jack, 20 and after the jacks are set the lever may be detached. The lower part of the body of the jack is provided with a laterally extending portion, forming a base 20, to prevent the jack from tilting.

25 The invention having been set forth, what is claimed as new and useful is:—

A lifting jack comprising a body consisting of a main V-shaped wood section having a lateral base at its lower portion, a 30 pair of triangular shaped wood sections secured on one face of the main section with

their perpendicular edges spaced in parallel relation to each other to form a guide channel, a pair of straps arranged one above the other and secured to the outer face of the 35 triangular section, a lifting jack member vertically adjustable in said channel under said strap, said lifting jack member having a plurality of apertures arranged in a vertical line, a cam member, means for connecting 40 said cam member eccentrically in any one of said apertures, whereby the marginal edge of the cam member may cam on the upper edge of the main section for raising and lowering the jack member, said cam member 45 having a socket for the reception of a handle, said cam when its pivotal point is at a diametrically opposite point to the engaging surface of the cam will hold the vehicle in supported position and when the cam is 50 moved to either side of a vertical center line the weight of the vehicle will cause said cam to rotate and its frictional engagement at its lower edge will prevent the rapid lowering 55 of the vehicle.

In testimony whereof I have signed my name to this specification in the presence of two subscribing witnesses.

BRITTAIN F. WALSER.
